UNITED STATES PATENT OFFICE.

EDWARD ASHTON SHARP, OF EPWORTH, COUNTY OF LINCOLN, ENGLAND.

LETTER-BOX.

SPECIFICATION forming part of Letters Patent No. 402,623, dated May 7, 1889.

Application filed February 29, 1888. Serial No. 265,756. (No model.) Patented in England October 20, 1886, No. 13,374.

To all whom it may concern:

Be it known that I, EDWARD ASHTON SHARP, residing at Epworth, in the county of Lincoln, England, have invented certain new and useful Improvements in Letter-Boxes, of which the following is a specification.

English Letters Patent No. 13,374, dated October 20, 1886, have been granted for this invention.

10 The invention consists in the novel construction and combination of the parts hereinafter fully described and claimed, whereby the safety of the contents of the letter-box is more fully assured.

15 In the drawings; Figure 1 is a vertical section through the letter-box, showing the sliding receptacle lowered; and Fig. 2 is a similar view showing the receptacle raised.

C is the letter-box, provided with the flat 20 front side A, having an opening or slit, a, for the letters.

B is a diagonally-arranged hollow receptacle, having openings at its upper and lower ends and a flat portion, b, which closes the 25 opening a when the receptacle B is lowered. The receptacle B has parallel sides, and slides within the box C.

E is a bell-crank, and e is a cord for raising the receptacle, which lowers by its own weight. 30 D is a receptacle at the lower part of the letter-box C, and which communicates with the receptacle B immediately it descends.

The receptacle B is first raised by the bell-crank, as shown in Fig. 2, and the letters are dropped into it. The weight of the receptacle causes it to descend as soon as the bell-crank is let go. It therefore assumes the position shown in Fig. 1, and the letters are automatically discharged into the receptacle D, from whence they cannot be abstracted 40 through the slit a.

What I claim is—

In a letter-box, the combination, with the diagonally-arranged hollow receptacle B, having separate openings at its upper and lower ends, of the bell-crank and cord for raising the said receptacle, the plane surface A, having an opening, a, for the introduction of letters into the receptacle, and the plane surface C and receptacle D, communicating with the receptacle B after its descent, whereby the letters are automatically discharged therefrom into the said receptacle D, substantially as set forth.

In witness whereof I have hereunto signed 55 my name in the presence of two subscribing witnesses.

EDWARD ASHTON SHARP.
